BACON-Straightening Device

Leonard De Moss, Des Moines, Iowa, assignor to
 Industrial Patents Corporation, Chicago, Ill., a
 corporation of Delaware

Application April 3, 1933, Serial No. 664,100

2 Claims. (Cl. 17—44)

This invention relates to means for the treatment of bellies or bacon slabs. When bellies or slabs of bacon are smoked, there is a tendency, especially when skinned bellies are used, to cause the bellies to curl or warp. As a result of such curling the appearance is less attractive, the slabs do not pack well and, moreover, the bacon does not slice well, especially in a slicing machine, as is the case when the slab lies flat.

10 One of the objects of the present invention is to provide a simple and effective device to be applied to the bellies preferably before smoking, the device being permitted to remain in place during smoking, thus preventing curling 15 during the drying coincident with smoking.

Other objects will be apparent from the description and claims which follow.

One embodiment of the invention is shown in the accompanying drawing in which:

20 Figure 1 is a perspective view of one embodiment of the device constructed in accordance with the present invention.

Figure 2 is a front view showing a bacon slab held in a conventional comb hanger with one of the devices applied to the lean side of the slab.

25 Figure 3 is a cross section taken through line 3—3 of Figure 2.

Figure 4 is a side view of the slab shown in Figure 2.

30 In the construction shown in the drawing, the device is made of No. 13 gauge tempered steel wire. The device is formed of two wires 1 and 2 which are complementary, being bent to form the spring arch 3 and soldered or otherwise affixed as at 4 and 5. Ends 6 are formed by bending the wires at right angles as at 7, the points 35 8 being formed by bending the ends of the wires as at 9.

35 In practice, two or more of the devices are applied to the lean side of the bacon slab, the points of one end being spaced from the points of the other end at a distance less than the normal distance between the ends when extended, in order that the spring tension of arch 40 3 may be utilized.

45 It will be seen by reference to Figure 1 and

Figure 3 that the points may be said to be forwardly extending, that is, extend in the general direction of the arc formed by the spring when the device is applied to a bacon slab and do not enter the slab at right angles to the surface whereby the spring merely urges the points inwardly and does not tend to tear the tissues.

In ordinary practice, the devices are applied to the unsmoked bellies and permitted to remain on the belly until after smoking has been completed and the meat has become chilled and set in the uncurled position.

Unlike the belly straightening devices which have been heretofore proposed, the device of the present application may be said to be self-adjusting. The spring is slightly compressed when the device is applied to the bacon slab and as a consequence exerts a constant pressure and, although it thus resists the tendency of the slab to shrink, the spring will give sufficiently to avoid any tendency to tear the tissue at the points of penetration.

Although but one specific embodiment of this invention is herein shown and described, it is to be understood that some of the details of construction shown may be altered or omitted without departing from the spirit of the invention as defined in the following claims.

I claim:

1. A bacon straightening device comprising two tempered steel wires complementally bent and joined together throughout the greater part of the central portion of their length, arched in this portion to form a spring, the ends being bent at right angles forming end pieces, the tips thereof being bent at right angles from the end pieces to form points.

2. A device of the class described comprising an arched central portion formed of wire and provided at each end with outwardly extending wire cross pieces, said arched portion being positioned wholly between the cross pieces, said cross pieces being provided with outwardly extending points formed of the material of the cross pieces.

LEONARD DE MOSS.
